UNITED STATES PATENT OFFICE

JOHN P. WILLIAMS, OF MALVERNE, NEW YORK, ASSIGNOR TO DUPLEX ELECTRIC COMPANY, OF NEW YORK, N. Y., A CORPORATION OF DELAWARE

AIR-VENT MEANS FOR VAULTS

Application filed May 25, 1928. Serial No. 280,527.

This invention relates to air-vent means for vaults and comprises a device which is mounted in a vault wall and extends therethrough and is adapted to be operated from the inside of the vault to provide a direct opening to the exterior of the vault. The purpose of such air-vent devices is to enable anyone locked in a vault, either under burglarious attack or accidentally, to conveniently open up the air passage afforded by the device and thus secure desired ventilation within the vault and communication through the wall thereof. The air passage thus afforded will enable the supply of air from the outside in sufficient degree to preserve the life of anyone imprisoned in the vault during any period of time until released.

It will be understood that bank vaults, as usually constructed, are air-tight at the interior, and have time-lock closure doors, and that therefore to preserve life within the vault under closed conditions it is necessary to provide emergency means for communication with the outside air.

It is the object of my present invention to provide an improved device of the character above indicated which will afford a vent area of a size conveniently and effectively adapted for the insertion of an intake tube from the inside of the vault and through the vent means to the outside of the vault when the vent is opened up, said tube being connected with ventilating fan means inside the vault whereby fresh air will be drawn into the vault and the foul air will be expelled therefrom through the excess area of the vent space which is not occupied by the intake tube.

A further object of my present invention is to provide simple and improved means whereby the turning or disarrangement of the closure plug of the vent means for its removal by manipulation from the outside of the vault will be entirely precluded, the plug member being locked against release by turnable operation and having itself no threaded connection with the body casing of the vent means which it closes, and being removable only by an inward pull upon a pilot wheel which turns freely upon the plug and is in locked connection with the body casing and thus it-

self forms locking means for the plug. My improvements are further designed to provide a device of this character which will possess advantages in point of simplicity, convenience, economy in construction, security, ease of operation, effectiveness, and general efficiency.

It will be understood that my improved air-vent means are adapted for effective employment through the walls of all types of vault construction, or large safes, or storage rooms or other compartments, under conditions in which an air-vent would be required to the interior in the eventuality of anyone being imprisoned therein.

In the drawings—

Figure 1 is a longitudinal sectional view through a portion of the vault wall, showing the improved air-vent means partly in side view and partly in section.

Fig. 2 is a sectional view corresponding to Fig. 1 and extending sectionally through the air-vent means.

Fig. 3 is a face view of a portion of the interior surface of a vault wall provided with my improved air-vent means.

Fig. 4 is a corresponding view at the exterior surface of the vault wall.

Fig. 5 is a detail cross-section on the line 5—5, Fig. 2.

Fig. 6 is a detail cross-section on the line 6—6, Fig. 2.

Fig. 7 is a detail cross-section on the line 7—7, Fig. 2.

Fig. 8 is a detail cross-section on the line 8—8, Fig. 2.

Fig. 9 is a detail cross-section on the line 9—9, Fig. 2.

Fig. 10 is a sectional view corresponding to Fig. 2, with the closure plug removed and showing the intake tube accommodated in the body casing.

Corresponding parts in all the figures are denoted by the same reference characters.

Referring to the drawings, 18 designates the outer casing or sleeve which constitutes the main tubular body of the device and extends longitudinally through the vault wall, this casing being preferably formed of a steel tubing. The exterior surface of this

body casing is preferably cylindrical and uniform throughout its length, and its interior bore is also of uniform diameter through its length except at the front and rear ends, the front end of the bore (which is at the outer face of the vault wall) being tapered in reduced diameter, as at 19, towards the end, to preclude any removal of the closure plug forwardly towards the outer side of the vault wall. The interior diameter of the bore of the casing is of sufficient area (in practice, usually approximately 3") to not only afford an ample air opening for the reception of an intake tube but also to provide additional space beyond the intake tube for the exhaust of the foul air. At its inner or rear end, which is at the interior face of the vault wall, the bore of the casing is preferably enlarged, as at 20, forming a stop shoulder, as at 21, beyond which the walls of the enlarged portion of the bore are threaded, as at 22, for engagement with a threaded portion of the hub of the pilot wheel as will be hereinafter described.

In mounting the device within the vault wall, the body casing 18 is surrounded by a concrete grout or filling which forms the interior wall mass, as at 24, and for the purpose of securely setting and locking the body casing in its position extending from the inner face to the outer face of the vault wall, the casing is provided with laterally projecting anchoring pins, 25, at suitable intervals, extending laterally into the grout mass and thus precluding any longitudinal or turning movement of the casing from its securely set position.

26 designates the closure plug for the body casing, which normally extends longitudinally within the bore of the casing and comprises a head, 27, at its outer or front end, which head fits snugly within and circumferentially conforms to the bore of the casing and has a tapered end portion, as at 28, snugly fitting the corresponding tapered portion 19 of the bore. Said head is carried by a longitudinal body rod, 30, extending towards the rear or inner end of the casing and beyond the same at the interior surface of the wall of the vault. The body rod of the closure plug is preferably of less diameter than the diameter of the head 27, whereby material reduction in the weight of the plug is effected and the manipulation thereof for insertion within or removal from the body casing 18 is conveniently facilitated.

The pilot wheel, 31, for governing the locking of the closure plug in its normal position and the releasing and withdrawal thereof, comprises a body, 32, adapted for convenient turning manipulation by the hands of the operator, and carrying a hub, 33, the inner end portion of which is axially recessed, as at 34, to form a cylindrical bore receiving the corresponding cylindrical inner end, 35, of

the body rod 30 of the closure plug member 26, the mounting being such that the pilot member turns freely thereon without any turning operation of the closure plug member. This mounting is preferably effected by a slip joint connection between the operating pilot wheel member and the end of the rod 30, the latter having a cylindrical circumferential groove, 36, receiving the ends of oppositely-located pins or studs, as at 37-37, 75 projecting from the hub 33 inwardly into the bore space thereof, the pilot wheel member thus having a revoluble but locked connection with the closure plug member and carrying the latter in its insertion into or removal from the body casing 18. The closure plug member and the operating pilot wheel member thus constitute a connected entity.

The preferred construction for providing the projecting pins or studs 37 is as herein shown, in which the pins are threaded from the outside through the wall of the hub 33, and the pins are locked in set position by means of set screws, as at 38, positioned in the wall of the hub 33 and having a flanged head, 39, accommodated in a surface recess in the hub and overlying the outer end portion of the threaded pins or studs 37.

The inner end portion of the hub of the pilot wheel is preferably disc shaped, as at 40, and of a diameter corresponding to the inner or rear end 20 of the bore of the body casing 18, the circumference of said end portion 40 being threaded, as at 41, to engage the internal threads 22 of the bore. Thus, when the pilot wheel is screwed home (by turning to the right), with the closure plug member 26 carried thereby and inserted in the bore of the body casing 18, the tapered head 28 of the plug is seated tightly within and against the tapered front or outer end portion of the bore in a fit which is both liquid and air tight, and the vent is thus securely closed by the plug in such manner that the latter cannot be withdrawn towards and from the outer face of the vault wall nor forced inwardly, its position being securely locked by the pilot wheel. In screwing home the pilot wheel, its threaded engagement with an entrance into the bore of the body casing, with relation to

relative adjustable conditions, is permitted by the enlarged inner end portion 20 of the bore within the limit of the stop shoulder 21 of the latter. To release the closure plug and open up the vent, it is only necessary to turn the pilot wheel reversely (to the left) to release its threaded connection with the body casing, in which operation the closure plug itself, which has no threaded connection with the bore of the casing, will not turn but the pilot wheel will freely turn on the plug, when the pilot wheel and the plug can be drawn as an entity into the interior of the vault and the closure plug thus removed from the body casing to open up the entire interior area of 130

the latter, the conditions being such that the plug is thus removable only from the inside of the vault.

In a preferred construction, the entire interior area of the bore of the body casing is preferably closed, and for this purpose the closure plug carries a cylindrical tubing, 42, having a closed inner end, as at 43, and extending longitudinally of the body rod or stem portion 30 of the plug which is normally within the bore of the casing, the outer or front edges of said tubing being seated and abutted against a cylindrical shoulder, 44, at the inner edge of enlarged front head portion 27 of the plug, and the closed inner or rear end of said tubing being secured to the rod or stem 30 by set screws, as at 45, engaging lateral stud plates, 46, upon the rod or stem 30. Thus, the closure plug member has substantially a diameter corresponding in longitudinal extent to the diameter of the bore of the body casing and the entire interior area of the bore is normally substantially closed, said tubing forming a skeleton body surrounding the reduced longitudinal rod or stem 30 of the plug and bringing the external diameter of the inner portion of the latter substantially uniform with the enlarged outer or head portion thereof.

I also preferably employ, in connection with the improved vent means, a heat resisting cap, 47, which is mounted at the outer face of the vault wall, coincident with the vent opening and closure plug, said cap piece being of full fireproof quality (for instance, asbestos) to protect the outer end of the vent means from the action of flame or heat. Said cap comprises a face plate or disc, 48, which seats against the usual plaster surface, 49, of the vault wall, and carries an inwardly projecting body portion accommodated in a recess in said plaster surface, said cap having a spring-clasp connection, 50, with a groove, 51, in a stud on the outer end of the closure plug, whereby when the latter is withdrawn inwardly from the vent the protective cap will fall to the floor and leave the end of the vent clear.

A special feature of my present invention and improvements is that the turning of the pilot wheel will not turn the closure plug in its normal position within the bore of the casing, but the turning of the wheel merely applies the necessary pressure upon the plug to seat it in locked position or to release it to permit it to be drawn from the vent by the pilot wheel. Thus the plug is held securely in position by means of pressure exerted by the pilot wheel and not by the usual conditions in which the closure plug itself has a threaded connection by which it is screwed into the body casing, and consequently any possibility of unscrewing the plug from the outside of the vault is entirely eliminated, as even if the plug is turned within the body

casing this action cannot release the threaded connection of the pilot wheel with the casing and will therefore not turn the pilot wheel nor affect the pressure it exerts to hold the plug in its tight connection at the outer end of the vent. In other words, the pilot wheel turns freely upon the fixed plug which it carries and exerts constant pressure when the plug is in normal position, and this pressure cannot be released by any turning of the plug itself.

My improved vent as herein described is especially adapted for effective usage and operation in connection with an auxiliary fan ventilating means, which latter can comprise an electric fan mechanism, shown at 52, mounted at the inside face of the vault wall and having a tubing, 53, of suitable length and preferably flexible, which can be inserted through the opened vent and which in operation will draw fresh air through said intake tube from the outside of the vault and create an exhaust whereby the foul air will be allowed to escape through the vent from the inside of the vault. The structure of the improved vent means is especially adapted to this purpose, the body casing 18 having a free and substantially uniform area throughout the length of its bore and being also structurally adapted to an enlarged diameter of its bore which will permit the rapid and convenient insertion of the fan intake tube through the bore, when the closure plug is removed, with the end of the tube projecting beyond the vault wall at the outer or front end, and thus affording in the relative construction, in which the intake tube is of materially lesser diameter than the diameter of the bore of the body casing, an ample space within the bore through which the foul air from inside the vault will exhaust while the fresh air is being drawn in by the intake tube. It will be further noted that the substantially uniform continuous construction of the bore of the body casing, as afforded by my present invention and improvements, offers no conditions of resistance to the free slideable insertion of the fan intake tube through the vent opening.

I do not herein claim the fan attachment in its relation to the improved vent means as herein set forth, the same forming the subject-matter of a separate application for patent, entitled "Air-vent fans for vaults," Ser. No. 280,528, filed May 25, 1928.

The operation and advantages of my invention will be readily understood. The improved air-vent device is at all times normally retained in closed position by engagement of the controlling pilot wheel with the body casing. Under emergency conditions, the only action necessary within the vault to afford instant opening of the air vent for effective ventilation or communication with the exterior, is merely the turning of the pilot

wheel to release its engagement with the body casing, whereupon the pilot wheel and the closure plug which it carries can be drawn inwardly within the vault to draw the closure plug entirely from the body casing and thus leave the bore of the latter entirely open and affording free air communication with the exterior of the vault. Then, in connection with the employment of the fan attachment as herein referred to, the electric fan can be started and its intake tube slidably inserted in the bore of the body casing towards the outer end thereof and projectively therefrom, whereupon the fresh air will be drawn into the vault and the foul air therein exhausted outwardly through the excess space in the bore of the body casing which is afforded by the greater diameter of said bore and the lesser diameter of the intake tube. The improved device thus affords a very simple and effective means which can be conveniently and instantly operated in a simple movement without excessive manual requirements, and an effective vent means which is proof against attack from the exterior of the vault.

I do not desire to be understood as limiting myself to the detail construction and arrangement of parts as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claims.

Having thus described my invention, I claim and desire to secure by Letters Patent:

1. An air-vent means of the class described, comprising a tubular body casing adapted to be secured in a wall and extend therethrough, said casing having a continuous longitudinal bore of substantially uniform diameter and unobstructed throughout its main length and having an outwardly tapered reduced diameter at its outer end, a plug forming a closure for said tube and having a correspondingly tapered outer end, said plug having a slidable mounting within said bore and being free from engaged connection with the wall thereof, a pilot-wheel member turnably mounted upon the rear or inner end of said plug, means securing the turnable connection of the pilot wheel and plug against longitudinal movement, said means consisting of a circumferential groove at the end of the plug and pins or studs entering laterally from the hub of the pilot wheel into said groove, whereby the pilot wheel and plug constitute an entity the parts of which are in connection but relatively turnable, and a hub portion carried by the pilot wheel and projectively entering the inner or rear end of said bore of the body cas-

ing and having a threaded engagement with the interior wall thereof.

2. An air-vent means of the class described, comprising a tubular body casing adapted to be secured in a wall and extend therethrough, said casing having a continuous longitudinal bore substantially unobstructed throughout its main length and having a reduced diameter at its outer end, a plug forming a closure for said tube and having a slidable mounting within said bore and being free from engaged connection with the wall thereof, said plug having at its outer or front end a head corresponding to and adapted to seat against the reduced front end of said bore and a rod or stem extending longitudinally and rearwardly from said head, a tubular casing surrounding said plug stem to compensate for the differing diameter of the plug head and stem and to afford a substantially uniform closure of the bore of the body casing at the stem portion of the plug beyond its head, and means engaging the inner or rear end of said stem for securing said plug to its front seat, said means being held against movement longitudinally of said stem.

3. An air-vent means of the class described, comprising a tubular body casing adapted to be secured in a wall and extend therethrough, said casing having a continuous longitudinal bore substantially unobstructed throughout its main length and having a reduced diameter at its outer end, a plug forming a closure for said tube and having a slidable mounting within said bore and being free from engaged connection with the wall thereof, said plug having at its outer or front end a head corresponding to and adapted to seat against the reduced front end of said bore and a rod or stem extending longitudinally and rearwardly from said head, a tubular casing surrounding said plug stem to compensate for the differing diameter of the plug head and stem and to afford a substantially uniform closure of the bore of the body casing at the stem portion of the plug beyond its head, controlling means turnably mounted upon the inner or rear end of said stem and engaging with the body casing to secure said plug to its front seat, and means securing the connection of the plug and turnable controlling means against independent longitudinal movement of the plug.

4. An air-vent means of the class described comprising a tubular body casing adapted to be secured in a wall and extend therethrough and a plug forming a closure for said tube and removable therefrom towards the inner side of the wall, a heat-resisting cap adapted to seat against the outer face of the wall and having a clasp connection with the outer end of said closure plug, whereby upon withdrawal of the plug the clasp connection will be released and the cap drop from engagement.

5. In air-vent means of the class described comprising a tubular body casing adapted to be secured in a wall and extend therethrough and a plug forming a closure for said tube and removable therefrom towards the inner side of the wall, means located in said tube for preventing forward movement of the plug within said bore, a heat resisting cap adapted to seat against the outer face of the wall, and having a clasp connection with the outer end of said closure plug, whereby upon withdrawal of the plug the clasp connection will be released and the cap drop from engagement.

15 In testimony whereof I have signed the foregoing specifications.

JOHN P. WILLIAMS.
